PRECISION GARMENT PATTERN GRADING TOOL

Isidore Sturman, Yonkers, N. Y.

Application September 3, 1954, Serial No. 454,181

3 Claims. (Cl. 33—11)

My present invention relates to a device for the grading of garment patterns and the like.

Devices of this description are used for tracing a given pattern in different positions parallel to one another and spaced apart by predetermined distances. Such positioning is conveniently accomplished by providing a holder for the pattern which is mounted on a support for movement in two dimensions.

It is an object of this invention to provide an improved device of the above character having means for accurately indexing the pattern holder in several positions, relative to its support, into which it may be selectively moved by rectilinear displacement in two orthogonal directions.

Another object of this invention is to provide, in a device of this type, an improved clamp for attaching either a one-piece pattern or a plurality of complementary pattern pieces to the holder.

The above and other objects and features of my invention will become more fully apparent from the following description of a preferred embodiment, reference being had to the accompanying drawing in which:

Fig. 1 is a top plan view of a pattern grader according to the invention;

Fig. 2 is a side elevational view of the device shown in Fig. 1;

Fig. 3 is a side elevational view, on a larger scale, of the movable holder forming part of the device of Figs. 1 and 2;

Fig. 4 is a top plan view similar to Fig. 1 but drawn to a smaller scale and also showing an extension of the holder clamp adapted to engage a plurality of pattern pieces;

Fig. 5 shows part of the clamp extension of Fig. 4 on a larger scale;

Fig. 6 is a fragmentary cross-sectional view taken on the line VI—VI of Fig. 5;

Fig. 7 is a cross-sectional view taken on the line VII—VII of Fig. 5; and

Fig. 8 is an enlarged, fragmentary cross-sectional view taken on the line VIII—VIII of Fig. 4.

Referring first to Figs. 1-3, there is shown a device generally designated 10 whose main parts are the following: A plate-like support 11, formed with a channel-shaped extremity 12 having screws 13 for attaching it to the edge of a table or the like (not shown); a carriage 14, slideable on support 11 and comprising a guide plate 15 which is guided for rectilinear movement, parallel to channeled edge 12, by means of grooved blocks 16, 17 rigid with support 11; and a holder 18, of essentially plate-like configuration, slideably guided for movement traverse to edge 12 by means of grooved blocks 19, 20 rigid with carriage 14.

An indexing strip 21 on guide block 17 is provided with indentations 22 adapted to receive the tip of a latch member 23 which is slideably guided in a housing 24 mounted on guide plate 15. A handle 25, projecting upwardly from latch 23 through a slot 26 in housing 24,

2

serves to withdraw the latch 23 from indentations 22 against the force of a compression spring 26.

A second indexing strip 27, on guide block 19, is provided with indentations 28 adapted to receive the tip of a latch member 29 which is guided in a housing 30 on holder 18 in essentially the same manner as is latch 23 in housing 24; the projecting handle of latch 29 is shown at 31.

The indentations 22 and 28 are preferably provided with suitable markings, e. g. in fractions of an inch (as shown on the drawing) or in millimeters, to determine the extent of displacement of the holder 18 from a normal or zero position. In Fig. 1 there has been illustrated, in dot-dash lines, the relative displacement between holder 18 and carriage 14 as well as that between carriage 14 and support 11; the latter displacement, for the sake of clarity, has been illustrated by showing support 11 in an alternative position, although it will be understood that generally the support will be stationary and carriage 14 along with holder 18 will be moved with respect thereto.

Suitable anti-friction means, e. g. balls or rollers, may be inserted between the relatively movable elements 11, 14 and/or 14, 18 if desired.

The illustrated relative displacement of carriage 14 and support 11 from zero position exposes a slot 32 (dot-dash lines, Fig. 1) in the base of carriage 14 through which pass several pins 33 serving to secure the guide block 17 to support 11.

As best seen in Fig. 2, the forward portion 34 of holder 18 curves downwardly so that its underside is flush with that of support 11, whereby the weight of the pattern-engaging clamp carried on this forward portion is directly supported by the surface of the table to which the device is attached. This clamp comprises a lever 35, pivotally mounted between a pair of lugs 36 rising from holder 18, and a pressure bar 37 pivotally attached to the front end of lever 35 by means of lugs 38. Bar 37 is provided with rubber pads 39 adapted to press a piece of cardboard or the like, bearing the desired pattern, against a first or lower clamp jaw represented by holder portion 34, the clamping force being supplied by a compression spring 40 inserted between the rear end of lever 35 and holder 18.

The pivotal mobility of bar 37, representing a second or upper clamp jaw, around the front end of lever 35 can be utilized for the purpose of attaching to the holder 18 an extension generally designated 41 and shown in Figs. 4-8. This extension comprises a supporting rail 42, of considerably greater length than bar 37, which is attachable to this bar by screws 43 when the bar is swung out of its normal position as illustrated in dot-dash lines in Fig. 5. Slidably mounted on rail 42 are a plurality of arms 44, each with a head 45 which embraces the rail 42 and can be tightened thereon by means of a screw 46. Each arm 44 serves, in turn, as a support for a plurality of L-shaped fingers 47 having spring clips 48 attached to them by rivets 49; fingers 47 are likewise provided with heads 50 which slidably embrace the associated arms 44 and can be immobilized with respect thereto by screws 51.

It will be apparent that each of the fingers 47 with its attached spring clip 48 may grip an individual piece of cardboard forming part of an overall garment pattern, or that several of these finger-clip assemblies together may engage such a pattern piece. Thus, single-piece patterns may be engaged by the clamps 34, 37 whereas multi-piece patterns can be conveniently mounted on the extension 41, using as many clip members thereof as required. The desired parallel displacement in two dimensions will in either case be effected by the withdrawal of latches 23, 29 from indentations 22, 28 and subsequent re-engagement therewith in accordance with the markings provided thereat.

My invention is, of course, not limited to the specific construction described and illustrated but may be embodied in a variety of modifications without departing from the spirit and scope of the appended claims.

I claim:

1. In a pattern grading device, in combination, a holder, said holder having a forward portion forming a first clamp jaw, a lever, first pivot means swingably mounting said lever on said holder, a pressure member, second pivot means swingably mounting said pressure member on said lever opposite said portion and forming a second clamp jaw, resilient means operatively connected with said lever and urging said jaws toward each other, and means on a side of said member normally facing said portion for securing an extension element to said member upon pivotal displacement of said member from a normal position.

2. A pattern carrier for a pattern grading device, comprising a holder provided with a forward portion forming a first clamp jaw, a lever, first pivot means swingably mounting said lever on said holder, a pressure member, second pivot means swingably mounting said pressure member on said lever opposite said portion forming a second clamp jaw, and extension clamp means including an elongated element transverse to said lever and projecting beyond said member, said element being removably secured to a side of said member normally facing said portion and being detachable therefrom upon

pivotal displacement of said member from a normal position.

3. In a pattern grading device, in combination, a support, a holder displaceably carried on said support, said holder having a forward portion overhanging said support and extending flush with the underside of said support, said portion forming a first clamp jaw, a lever, first pivot means swingably mounting said lever on said holder, a pressure member, second pivot means swingably mounting said pressure member on said lever opposite said portion and forming a second clamp jaw, resilient means operatively connected with said lever and urging said jaws toward each other, and means on a side of said member normally facing said portion for securing an extension element to said member upon pivotal displacement of said member from a normal position.
